(57) **CLAIM**

The ornamental design for a pedal, as shown and described.

DESCRIPTION

FIG. 1 is a perspective view of a pedal showing my new
design;

FIG. 2 is a front elevational view thereof;

FIG. 3 is a rear elevational view thereof;

FIG. 4 is a right side elevational view thereof, wherein the
broken lines illustrate environmental structure that forms no
part of the claimed design.

FIG. 5 is a left side view thereof;

FIG. 6 is a top plan view thereof;

FIG. 7 is a bottom plan view thereof;

FIG. 8 is a view showing the pedal in a position of use,
wherein the broken lines illustrate environmental structure
that forms no part of the claimed design; and,

FIG. 9 is another view showing the pedal in a position of use,
wherein the broken lines illustrate different environmental
structure that forms no part of the claimed design.
